(57) **CLAIM**

The ornamental design for a cleaning brush handle, as shown and described.

DESCRIPTION

FIG. 1 is a top perspective view of a cleaning brush handle, showing my new design;

FIG. 2 is another side perspective view, shown in a different configuration and in an environment;

FIG. 3 is a front view thereof;

FIG. 4 is a rear view thereof;

FIG. 5 is a left side view thereof;

FIG. 6 is a right side view thereof;

FIG. 7 is an enlarged plan view of its top surface; and,

FIG. 8 is an enlarged plan view of its bottom surface.

In the drawings, the broken lines illustrate portions of the cleaning brush handle that forms no part of the claimed design. In FIG. 2, the broken lines show both environment and portions of the cleaning brush handle that forms no part of the claimed design.
